UNITED STATES PATENT OFFICE.

GEORGE H. MILLIGAN, OF GASTONIA, NORTH CAROLINA, ASSIGNOR OF SEVENTY-SEVEN AND ONE-HALF PER CENT TO INTER-CAROLINAS MOTOR BUS COMPANY, INCORPORATED, OF GASTONIA, NORTH CAROLINA, A CORPORATION OF NORTH CAROLINA; FIFTEEN PER CENT TO JOEL W. WRIGHT AND SEVEN AND ONE-HALF PER CENT TO B. T. HARRELSON, BOTH OF GASTON COUNTY, NORTH CAROLINA.

LINE-PAINTING MACHINE.

Application filed December 11, 1924, Serial No. 755,229. Renewed February 4, 1926.

In the control of traffic it is customary to provide lines upon the highways and streets generally, such lines being broad and painted upon the surface so as to withstand usage. These lines are usually painted upon the surface by hand with the result that they are maintained at some considerable expense in addition to the original cost for labor.

10 In accordance with the present invention a machine is provided and adapted to be traveled over the surface and automatically paint the lines thereon, said machine embodying a container or reservoir for holding the paint in bulk, a rotary brush for applying the paint to the surface and distributing means for controlling the flow of the paint from the reservoir to the brush, the latter being detachable to admit of 20 cleaning when not required for immediate use.

Other objects and advantages will be apparent and suggest themselves as the nature of the invention is understood.

25 While the drawings illustrate an embodiment of the invention it is to be understood that in adapting the same to meet different conditions and requirements, various changes in the form, proportion and minor 30 details of construction may be resorted to without departing from the nature of the invention.

Referring to the accompanying drawings forming a part of the specification,

35 Figure 1 is a side view of a line painting machine embodying the invention,

Figure 2 is a top plan view of the machine,

Figure 3 is a sectional view on the line 3—3 of Figure 2,

40 Figure 4 is a detail view on the line 4—4 of Figure 3,

Figure 5 is a detail sectional view on the line 5—5 of Figure 3, and

45 Figure 6 is a detail sectional view on the line 6—6 of Figure 3.

Corresponding and like parts are referred to in the following description and designated in the several views of the drawings by like reference characters.

50 The machine embodies a suitable frame 10 which is mounted upon ground wheels 11,

which are fast to an axle 12 so as to rotate therewith. A handle 13 is applied to the frame 10 and provides convenient means for trundling the machine over the surface 55 upon which the line is to be painted. A pulley 14 is fast to the axle 12 and a crossed belt 15 connects the pulley 14 with the pulley 16 fast to an axle 17, upon which is mounted a rotary brush 18. The crossing of the belt 60 15 results in rotating the brush 18 in a reverse direction to the ground wheels 11, with the result that the brush tends to resist the speed and to positively apply and spread the paint.

65 A reservoir or container 19 is mounted upon the frame 10 and holds the paint to be applied to the surface when lining the same. A pipe 20 connects with the lower portion of the reservoir 19 and is provided 70 in its length with a controlling valve 21 which is at all times under control of the operator by means of a rod 22 which extends within convenient reach of the grip of the handle 13. A distributor 23 is connected 75 with the pipe 20 and delivers the paint to the brush 18 and this distributor is formed with outwardly flared sides and with a top and bottom arranged with a restricted opening therebetween, and having grooves in its 80 bottom to direct the paint to the surface of the brush. A catcher 24 is provided to receive surplus paint and prevents the same from dropping upon the surface. Plates 85 25 are applied to opposite sides of the brush to prevent spreading thereof and to prevent waste of paint and insure the formation of a line of uniform width. The drip catcher 24 connects the guard plates 25 in the rear of the brush. Hangers 26 are connected at their lower ends to the guard plates 25 and are adjustably connected to the frame 10 by means of a rod 27 or like part. In this manner the brush 18 may be elevated and the removable feature of the axle 17 admits of the brush 18 being detached 90 for cleaning or placed in a vessel containing water to prevent hardening of the paint when the brush is not required for immediate service.

95 A smoothing brush 28 is disposed to operate in the rear of the lining brush 18 to

spread and smooth the paint and this brush is detachably connected to the holder 29, which may form a part of the main frame or applied thereto as required. The smoothing brush 28 may be of any construction and usually consists of an ordinary flat paint brush clamped by means of the handle to the holder 29.

In practice the paint is supplied to the reservoir or container 19 and the machine is trundled over the surface upon which it is required to paint a line, and by properly manipulating the rod 22 the valve 21 may be operated to control the supply of paint to the brush 18, and as the machine is propelled over the surface the brush 18 applies the paint to the predetermined line.

What is claimed is:—

1. A machine for painting a line upon the surface of a highway or street, the same comprising a supporting frame, a reservoir mounted thereon and adapted to hold the paint, a rotary brush, means for supplying paint to the brush from the said reservoir and means for applying rotary motion to the brush, and a drip catcher associated with the brush for receiving surplus paint.

2. A machine for painting a line upon the surface of a highway or street, the same

comprising a supporting frame, a reservoir mounted thereon and adapted to hold the paint, a rotary brush, means for supplying paint to the brush from the said reservoir and means for applying rotary motion to the brush, and a smoothing brush operating in the rear of the line painting brush.

3. A line painting machine, comprising a supporting frame, a reservoir mounted thereon to hold the paint, a rotary brush, plates on the two sides of the brush to prevent spreading thereof, a valved pipe for supplying paint to the upper side of the brush from the reservoir, and a drip receptacle for surplus paint supported by said plates.

4. A line painting machine, comprising a supporting frame, a reservoir mounted thereon to hold the paint, a rotary brush, plates on the two sides of the brush to compress it, a valved pipe for supplying paint to the upper side of the brush from the reservoir, a drip receptacle for surplus paint supported by said plates, and a resiliently supported smoothing brush in the rear of the rotary brush.

In testimony whereof I affix my signature.

GEORGE H. MILLIGAN.
